UNITED STATES PATENT OFFICE

EMERY VAJDA, OF CLEVELAND, OHIO, ASSIGNOR, BY MESNE ASSIGNMENTS, TO
WM. F. WEHRLE

PORTABLE PHYSICIAN'S AND DENTIST'S LIGHT AND SWITCH THEREFOR

Application filed November 2, 1928. Serial No. 316,773.

My invention relates to low voltage electrical appliances adapted for being operated by connection with outlets of ordinary electric light circuits of 110-120 volts, for example. 5 More particularly my invention relates to improvements in the low voltage lights for physicians and dentists set forth in my application for patent, Serial No. 264,223, filed March 23, 1928, and in my application for 10 patent, Serial No. 290,454, filed July 5, 1928.

In this electrical appliance, as well as other low voltage appliances, it is essential that the voltage for the appliance be reduced from the impressed voltage of the lighting circuit, to the required voltage for the appliance. 15

On the other hand in the case of lights for physicians and dentists, from the standpoint of safety for patients, and for ease of operation, it is undesirable that any substantial quantity of heat be given off by the light or by the conductors immediately adjacent the light handle.

Moreover, a conveniently located switch is 25 essential for the proper use of such lights by physicians and dentists.

Accordingly the objects of the present improvements include the provision of a low voltage light, arranged with resistance conductors, plain conductors, a connector between the conductors, a switch, and a connector plug, in a novel manner whereby the connector plug may be inserted into the outlet of an ordinary electric light circuit, and the 30 desired low voltage will be impressed upon the light, and the undesired giving off of heat near the light will be substantially eliminated.

Further objects of the improvements include the provision of a compact and easily assembled telescopic switch adapted for embodiment in a handle which also mounts the light socket. 40

These and ancillary objects are attained in the present improvements, as will be herein-after set forth in detail and claimed.

A preferred embodiment of the invention is illustrated in the accompanying drawings 50 forming part hereof, in which

Figure 1 is an elevational view with portions broken away of the improved light for physicians and dentists;

Fig. 2, an enlarged longitudinal sectional view of the handle illustrating the improved telescopic switch; and 55

Fig. 3, a perspective view illustrating parts of the handle and switch about to be assembled.

Similar numerals refer to similar parts 60 through the drawings.

The improved light for physicians, dentists, and the like is indicated generally at 10, and includes the improved tubular handle 11 of relatively small diameter, and 65 preferably made of insulating material, and in one end of which is mounted a lamp socket 12.

The socket is adapted to have screwed therein, the base 16a of an elongated electric lamp 16, the bulb 17 of which is preferably 70 in the form of a cylindric tube of small diameter and having a closed outer end 18 and joined at its other end with the base 16a in the usual manner, and the bulb being 75 evacuated, and there being a filament 19 located within the bulb adjacent the outer end 18 thereof, one terminal of the filament being connected in a usual manner with the screw cup 16b of the base, and the other terminal 80 of the filament being connected with the center contact 16c of the base, there being insulating material between the center contact 16c and the screw cup 16b, in the usual manner, and the bulb 17 is preferably opaque 85 throughout the greater portion of its length.

The lamp is thus of usual construction, and in order to enable the provision of the relatively small diameter required for the elongated tube bulb 17, and as a safety measure, it is desired that the filament 19 be lighted by a current of relatively low voltage which may be for example 10 volts in lights for physicians' use, or 6 volts in lights for dentists' use. 90

On the other hand it is desirable that the lamp be adapted for operation by connection as by means of a plug connector 20 with an ordinary electric light circuit of 110-120 95 100

volts, and that a switch be provided for controlling the illumination of the lamp.

It is moreover desirable that the potential difference between the terminals of the switch be as low as possible.

- 5 Moreover as aforesaid it is desirable that substantially no heat be given off at or near the light.

Accordingly a resistance cable 22 is utilized 10 to connect the plug connector 20 with one side of a connector 21, and this resistance cable is itself covered with asbestos or other suitable heat insulating material, and for a 10 volt light, has a resistance of substantially 15 48 ohms per foot and is 7 feet in length. For lights of other voltages the length or resistance per foot of the cable 22 is suitably varied.

The other side of the connector 21 is connected by an ordinary cable 23 which may 20 be 3 feet long, through the improved telescopic switch 24 with the socket in the tubular handle 11 in a novel manner.

The improved switch 24 is operatively 25 mounted within the tubular handle 11, and includes a longitudinal mounting member 25 preferably made of insulating material, which is adapted to be inserted into the handle through the lower cable end opening 30 26 thereof.

The lamp socket 12, preferably includes 35 one terminal 27, which is in the form of an internally threaded cup made of conducting material, and into which the externally threaded base 16a of the lamp 16, is arranged to be screwed.

The bottom wall 29 of the cup is provided 40 with a central aperture therein which registers with the opening in a wedge tapered tubular switch terminal 30, which is preferably formed integral with the cup 27.

The other terminal of the lamp socket, for connecting with the lamp base center contacts 16c, is preferably in the form of an enlarged 45 head 31 at the outer end of a conductor rod 32, which longitudinally extends through a bore axially located in the mounting member 25.

The socket end 33 of the mounting member 50 25, is of reduced diameter to fit within the registering apertures in the switch terminal 30 and the socket bottom wall 29, and to extend beyond the socket side of the bottom wall 29, so that the socket terminal 55 head 31 will be properly insulated from the socket cup terminal 27.

The other switch terminal is provided by 60 a longitudinally extending conducting strip 34, preferably curved about the cylindric middle portion 35 of the mounting member 25.

As aforesaid, the mounting member 25 is 65 preferably made of insulating material, whereby the conductor rod 32 is insulated from the conducting strip 34.

In the event that it is desired to make the mounting member in part of conducting material, it is obvious that the conductor rod and the conducting strip may be insulated from each other and from the mounting member by the use of insulating coatings thereon.

A movable contact member 36, preferably 70 in the form of a telescopic sleeve, and which is slidably inserted over and fits the conducting strip 34, is arranged for movement towards the tubular terminal 30 for telescopically electrically connecting the same with the conducting strip 34, and for movement 75 away from the tubular terminal 30 for breaking the electrical connection.

The wedge tapered tubular terminal 30 is arranged to telescopically fit in the adjacent beveled end 37 of the sleeve 36.

The conducting strip 34 is secured to the 80 mounting member 25 by means of a screw 38, which also serves to connect the conducting strip with one of the conductors 39 of the cable 23.

A screw 40 serves to secure the conductor 90 rod 32 within the mounting member 25, and to connect the same with the other conductor 41 of the cable 23.

The mounting member 25 and attached 95 parts are secured within the tubular handle 11 by means of one or more screws 42, each of which preferably passes through the side wall of a closure sleeve 43 preferably of insulating material which fits about the cable end of the tubular handle 11, and which then passes through the tubular handle 11 into a suitable threaded socket 44 provided at the cable end 100 of the handle 11.

The sleeve 43 is preferably provided with 105 an inwardly projected flange 45, which serves to secure a spiral guard 46 for the cable 23.

Means for moving the ring or sleeve contact member 36 is provided by a screw 47 which is screwed into the contact member 36 through a longitudinally extending slot 48 in the tubular handle 11, and a knob 49 preferably of insulating material may be cemented upon the outer end of the screw 47.

By these means a very easily assembled 115 socket and switch structure are provided for the purpose herein set forth, the novel switch structure being certain and sure in its operation at all times.

It is obvious that this improved telescopic 120 switch structure may be adapted for other purposes, it is not intended to limit its use to that particularly set forth herein.

I claim:

1. An electrical switch including a handle, a pair of lamp terminals mounted in the handle, an insulation member located in the handle and extending between the terminals, one of the terminals being adapted for connection with a conductor, a conducting strip mounted upon the insulation member and adapted for 125 130

- connection with another conductor, a contact member movably mounted in the handle and slidably contacting with the strip, the contact member being movable into engagement with the other terminal for connecting the strip with the other terminal by movement in one direction and for breaking the connection by a movement in the opposite direction.
2. An electrical instrument including a handle, a socket in the handle adapted for mounting an electrical appliance of relatively low voltage, the socket including a pair of lamp terminals, an insulation member located in the handle and extending between the terminals, one of the socket terminals being adapted for connection with a conductor, the other socket terminal being tapered, a conducting strip mounted upon the insulation member and adapted for connection with another conductor, a contact member movably mounted in the handle and slidably contacting with the strip, the movable contact member being movable into wedge engagement with the tapered terminal for connecting the strip with the tapered terminal by a movement in one direction and for breaking the connection by a movement in the opposite direction.

In testimony that I claim the above, I have
hereunto subscribed my name.

EMERY VAJDA.
